UNITED STATES PATENT OFFICE.

TAYLOR W. HEINTZELMAN AND JAMES G. CAMP, OF SACRAMENTO,
CALIFORNIA.

OIL-BURNING STEAM-BOILER.

No. 857,170.

Specification of Letters Patent.

Patented June 18, 1907.

Application filed April 20, 1904. Serial No. 204,003.

To all whom it may concern:

Be it known that we, TAYLOR W. HEINTZELMAN and JAMES G. CAMP, both of Sacramento, in the county of Sacramento and State of California, have jointly invented a certain new and useful Improvement in Oil-Burning Steam-Boilers, of which improvement the following is a specification.

The object of our invention is to provide means for effectively and economically generating steam, in boilers of the locomotive, marine, stationary, and other types, by the combustion of liquid hydrocarbons, such means being designed to attain complete combustion of the fuel within the firebox, and the application of the evolved heat to the entire heating surface of the firebox, without injury to the fire-box sheets or inducing leaky flues, and without unduly heating the front end or smoke arch, thereby avoiding the objections heretofore encountered of leaky steam pipes and tubes in front end.

A further and special object of our invention is to enable the brick arch ordinarily employed to be dispensed with, thereby materially reducing the quantity of brick required.

The improvement claimed is hereinafter fully set forth.

In the accompanying drawings: Figure 1 is a vertical, longitudinal, central section through the firebox and adjoining portion of the waist of a steam boiler illustrating an application of our invention; Fig. 2, a rear view, in elevation, of the same; Fig. 3, a vertical transverse section, on the line *a-a* of Fig. 1, and; Fig. 4, a vertical central section, on an enlarged scale, through the burner.

Our invention is herein exemplified as embodied in a locomotive boiler of the ordinary narrow and deep firebox type, but, as will appear upon a consideration of its essential structural and operative features, it is not limited in application to this or any other special type or form of steam boiler, being adapted to use in any of the various constructions which are provided with a firebox or furnace and tubes or flues leading therefrom. In the instance herein shown, the inside firebox, 1, is of the usual form and is closed at its top by a crown sheet, 2, and surrounded by vertical water spaces 3, the bottoms of which are closed by a mud ring, 4, as in ordinary lo-

comotive boiler practice. The outside firebox, 5, is connected to the waist, 6, through which the tubes, 7, pass from the tube sheet, 8, to a smoke box of the usual form (not shown) at the front end of the boiler.

In the practice of our invention, the inside firebox, 1, is closed at bottom by a sheet or plate metal box or casing, 9, which, as it corresponds substantially, in general form and location, with the ordinary ash pan of boilers in which solid fuel is used, will be herein descriptively referred to by that term. The ash pan, 9, is closed at all points except as to a central draft opening or flash hole, 10, located toward its rear end, and is provided, on its bottom, sides, and rear, with a fire brick lining, 11, which extends upwardly for a short distance at its sides, and for a greater distance at its rear, into the inside firebox, 1.

In all oil burning appliances heretofore proposed or used in connection with steam boilers, so far as our knowledge and information extend, it has been the practice to introduce a jet of atomized hydrocarbon into the firebox at or near its rear end, or that farther from the tube sheet, so that the flame from the burner is projected in the same direction as the traverse of the draft, that is to say, forwardly toward the tube sheet. In constructions of this type, in order to protect the tube sheet and tubes from the direct action of the high heat of the flame, as well as to direct the heat, as far and as uniformly as may be, over the surfaces of the side, back, and crown sheets of the firebox, it has been found necessary to locate a transverse brick arch in the fire box, adjoining, or a short distance in the rear of, the tube sheet, and below the tubes. It will be obvious that the brick arch referred to involves a material increase of cost, weight, and time required for installation and renewals or repairs, and, moreover, the deflection or change of direction of the flame which it effects, has not been found to accomplish, as fully as is desirable, the application of its heat with substantial uniformity to the surfaces of the inside firebox.

The leading and characteristic feature of our invention, which has been developed with the object of not only dispensing with the ordinary brick arch, but also of obtaining a more uniform and effective application of the heat from the burner to the heating sur-

faces of the firebox than has usually been attainable when the arch is used, consists in combining, with a firebox and a lower ash pan floor, a burner which delivers its flame 5 rearwardly, or in opposite direction to the draft, above said floor, without obstruction from arches, bridge walls, or other analogous members, and a rear draft opening through which a current of air is directed upon the 10 flame, which it upwardly deflects, the flame being thereafter caused to travel forwardly, below the crown sheet, to the tubes, by the draft through the same. Under this construction, the hydrocarbon fuel is consumed 15 in the firebox, imparting substantially uniform heat to all the heating surface thereof, without direct action of the flame from the burner upon the tube sheet and tubes, and without highly heating the smoke box and 20 contained steam pipes.

Under our invention, we provide an oil burner, 12, which may be of any suitable and approved construction, various types being familiar to those skilled in the art, and which 25 is located in front of the firebox, with its discharge or delivery nozzle, 12^a, extending rearwardly and opening thereinto. In the instance shown, the delivery nozzle passes through an opening in the front sheet of the 30 ash pan, 9, but it will be obvious that, if preferred, it may be led through a hollow stay or sleeve in the lower portion of the front water space, 3, as has been done in a number of cases by us, with equally satisfactory results 35 in practice. Oil is supplied to the burner through an oil supply pipe, 13, leading from a suitable tank or receptacle, and controlled by a firing valve, 13^b, which is actuated by a hand lever 13^a, through connections 14, 15 40 and 16. The oil is, as in ordinary practice, preferably heated by means of a superheater, 17, through which the oil supply pipe, 13, passes on its way to the burner, and which is supplied with steam from the boiler through 45 a pipe, 18, controlled by a valve, 19, and is atomized and discharged into the firebox, by a jet of steam admitted to the burner through a pipe, 20, controlled by a cock, 21. The detailed construction of the burner and its accessories is not, as above indicated, an essential 50 of our invention, and the same may be varied in the discretion of the skilled constructor, without departure therefrom. The burner shown is, however, one which is simple, durable, and inexpensive, and is now 55 successfully operating in regular service.

A blower pipe, 22, controlled by a valve 23, serves to maintain draft on the fire when the steam is shut off and the exhaust 60 steam blast, which is operative in running, is consequently not effecting draft through the tubes. It will be obvious that the brick flooring of the ash pan is open above the flash hole 10, so as to permit free passage of 65 air through the same, and the flash hole may,

if desired, be controlled by an adjustable regulator or damper.

In the operation of our invention, the flame of the mixture of atomized oil and steam which is delivered rearwardly from the discharge nozzle of the burner, passes above the ash pan floor of the firebox, and the draught of the exhaust, by which air is drawn in through the flash hole, being in the opposite direction, tends to raise the flame 75 slightly in its rearward traverse. When the flame reaches the plane of the rearwardly located flash hole, it is deflected upwardly by the entering current of air and thereafter passes forwardly through the firebox, below 80 the crown sheet, to the tubes. The oil is found, in practice, to be consumed in the inside firebox, with a very uniform application of heat to the heating surfaces thereof, and the flame produced, which is of a lemon 85 color, is soft and does not injure the crown sheet or tube sheet, or cause leaky tubes, a substantial advantage having been gained, in this latter particular, over appliances heretofore used in the same service. 90

We claim as our invention and desire to secure by Letters Patent:

1. The combination, with a firebox of a locomotive boiler, of a fire brick lined ash pan extending continuously from the front to the rear of the firebox, a fire brick lining abutting against the rear wall of the firebox, a hydrocarbon burner extending into the firebox at or near the front end thereof and having an uninterrupted discharge therefrom to said rear lining, and a direct draft opening formed in the bottom of the ash pan adjacent to the rear end thereof, whereby the passage of heat from the burner is permitted throughout the length of the firebox and a flame is turned back toward the tube sheet to effect complete combustion. 100

2. The combination, with a firebox of a locomotive boiler, of an ash pan extending continuously from the front to the rear of the firebox, a refractory lining on the bottom, sides, and rear of the ash pan, said lining abutting against the walls of and extending into the firebox, a hydrocarbon burner extending into the firebox at or near the front end thereof and having an uninterrupted discharge therefrom to the rear lining, and a direct draft opening in the bottom of the ash pan adjacent to the rear thereof, whereby the passage of heat from the burner is permitted throughout the length of the firebox and a flame is turned back toward the tube sheet to effect complete combustion. 115

3. The combination, with a firebox of a locomotive boiler, of a fire brick lined ash pan extending continuously from the front to the rear of the firebox, a fire brick lining abutting against the rear wall of the firebox, a hydrocarbon burner extending into the firebox at or near the front end thereof and 125 130

having an uninterrupted discharge therefrom to said rear lining, and a direct draft opening formed in the bottom of the ash pan adjacent to the rear end thereof which establishes draft through the firebox to the boiler tubes in opposite direction to the traverse of flame from the burner, thereby turning the flame toward the tube sheet without

preventing the heating action on the rear portion of the firebox and supplying oxygen for complete combustion.
